UNITED STATES PATENT OFFICE

JOSEPH BREZA, OF PARIS, FRANCE

FINGER EXERCISER

Application filed May 16, 1927, Serial No. 191,840, and in Belgium March 21, 1927. Renewed November 16, 1929.

The present invention has for its object the production of a device specially intended for exercising the fingers of a musician.

The invention consists of a metal spring which is so shaped as to adapt it to be introduced and maintained between the second and third fingers; and the use of which, besides giving the musician's fingers and wrist more expansive force, promotes easy motion of the fingers upon various instruments, whether keyboard, stringed, or wind instruments.

This invention has been shown in the accompanying drawing, merely by way of example, wherein:

15 Fig. 1, is a plan view of the device;
Fig. 2, is the corresponding vertical section.

In Fig. 1, numeral (1) indicates the curved parts for insertion of the player's fingers, and (2) is the gap between branches; one can realize the possibility of stretching-out the metal branches which, thanks to their resiliency, enable the user to acquire the extensive force referred to.

25 It should be understood that this invention lends itself to many modified embodiments, without departing from the spirit of the invention as defined in the appended claim.

Having now particularly described and ascertained the nature of my invention, I declare that what I claim as new, and desire to secure by Letters Patent, is:—

30 A wrist and finger exercising device comprising a spring composed of a pair of branches spaced apart and a member connecting the branches together at one end, said branches being curved in opposite directions and arranged with their concave sides outermost, said branches and said connecting member being provided with oppositely curved merging portions, the convex sides of which are outermost.

40 In testimony whereof I affix my signature.
COUNT JOSEPH BREZA.
